UNITED STATES PATENT OFFICE.

HENRY E. WAITE, OF NEW YORK, N. Y.

DESIGN FOR A CABINET FOR ELECTRICAL APPLIANCES.

SPECIFICATION forming part of Design No. 19,763, dated April 15, 1890.

Application filed February 17, 1890. Serial No. 340,796. Term of patent 7 years.

To all whom it may concern:

Be it known that I, HENRY E. WAITE, a citizen of the United States, and a resident of the city, county, and State of New York, have invented a novel Design for Cabinets for Electro-Medical and Electro-Surgical Appliances, of which the following is a specification.

My design relates especially to cabinet-cases for electro-medical and electro-surgical appliances.

In the accompanying drawing I have illustrated a face view showing a case embodying my design.

The leading feature of my design consists in a base-piece having a series of open shelves and a top piece resting thereon, both of the pieces being substantially rectangular in shape and provided with ornamental outlines, in substance as shown.

The lower case A is rectangular in general contour, with the shelves B extending horizontally across beneath the head-piece C. A rod D extends below the head-piece, and curtains E are hung thereon. The top piece is also substantially rectangular in contour, and a drawer G extends across its lower portion, while at the upper portion is a shelf H, parallel with the drawer. Upon each side of the top case and above the lower case are ornamental brackets K.

The whole design presents to the eye the effect of two rectangular cases, one mounted upon the other and having parallel shelves and drawers, the edges or contours being ornamented, substantially as shown.

What I claim is—

A design for a cabinet for electro-medical and electro-surgical appliances, substantially as herein shown and described.

In testimony whereof I have signed my name to this specification in the presence of two subscribing witnesses.

HENRY E. WAITE.
